ROBERT P. SMITH, OF CHICAGO, ILLINOIS, ASSIGNOR, BY MESNE ASSIGNMENTS, TO SERVICE INVENTION & DEVELOPMENT COMPANY, A CORPORATION OF DELAWARE.

STAMP-HANDLING MECHANISM.

1,382,578.

Specification of Letters Patent.

Patented Mar. 2, 1920.

Application filed October 6, 1916. Serial No. 124,014.

To all whom it may concern:

Be it known that I, ROBERT P. SMITH, a citizen of the United States, residing at Chicago, in the county of Cook and State of Illinois, have invented certain new and useful Improvements in Stamp-Handling Mechanism, of which the following is a specification.

The present invention relates to improvements in stamp handling mechanism and the like and, in some of its features, it has to do particularly with a power-operated stamp-dispensing mechanism suitable for use in a coin-controlled stamp-vending machine, carrying its stamp-stock in roll form.

Among the objects of the present invention are to provide a stamp-delivering mechanism that will positively expel the stamps and will positively prevent surreptitious withdrawal of more stamps than the proper functioning of the machine has caused to be ejected; that will operate under the control of appropriate manual control-instrumentalities to deliver variable quantities of stamps of different denominations at the will of the user; that will be easy to operate and yet substantially proof against such maloperation as might injure the mechanism; that automatically will compensate for variation, within practical limits in distances between perforation rows in the stamp strips; that is adapted to be automatically controlled by, and is capable of automatic control over associated machine elements; and that is simple and inexpensive in construction and efficient in operation.

Other and further objects of the invention will become apparent to those skilled in the art from the following description taken in conjunction with the accompanying drawings, wherein is illustrated an embodiment of the invention in a form particularly intended for use as part of a coin-controlled stamp-vending machine, although in simplified form appropriate portions of the mechanism may be used in simple machines for handling stamps and delivering them individually.

In the drawings—

Figure 1 is a side elevation with parts broken away of the stamp section;

Fig. 2 is a front elevation thereof;

Fig. 2^a is a representation, made diagrammatic, for purposes of simplicity of illus-

tration only, of certain supplemental parts 55 that complete a self-contained coin-operated vending machine embodying the present invention, such diagram being substituted for detailed illustration of much more complicated apparatus with which, commercially, 60 the mechanism embodying this invention is in fact associated.

Figs. 3, 4 and 5 are sections on line 3—3, 4—4 and 5—5 of Fig. 1;

Fig. 6 is a sectional detail on line 6—6 of 65 Fig. 7.

Fig. 7 is a section on line 7—7 of Fig. 6.

Figs. 8, 9 and 10 are enlarged sectional details of the stamp moving wheel.

The specific mechanism shown is adapted 70 for the handling or vending of two rolls of stamps of different denominations, for instance specifically, one-cent stamps and two-cent stamps, and the machine as a whole may vend at one operation any number of 75 either or both kinds of stamps that will total, in value, a certain amount.

The stamp strip handling means.

A suitable frame 20, of the stamp section, 80 shown as carried by the frame 20^a of the portion of the machine that carries the coin-controlled mechanism, affords support for the stamp handling mechanism and for the two stamp rolls A, of one and two-cent 85 stamps, that are carried in the top of the machine. 21 indicates a shallow tray for holding the two stamp rolls. These rolls bear against loose idler rollers 22, 22', and each strip is led over a guide roller 23 or 23', 90 down a suitable guide channel 24 in the face plate of the frame, to a throat 25 leading tangentially to a pin-feed "stamp wheel" or delivery wheel 26 that may pass the stamps out through a mouth or orifice 27. 95 Of course the stamp strips, exposed to view in the channels 24, are closed by glass suitably secured to overlie the strips, but the glass may be part of an exterior cabinet not forming part of the present invention. 100 With respect to the mechanism for handling the two stamp rolls, many parts are duplicates, and in general, only one of such duplicated parts is herein enumerated, the other kindred part being indicated by a similar 105 numeral differentiated by the exponent prime (').

In commercial practice it is true that in

rolls of stamps provided by the Government the spacing between perforation rows in the stamp strip varies quite materially, say, as much as $1/32''$ or more, so that the stamps 5 are not all of the same size; and one of the objects of the present invention is to provide a mechanism that will automatically compensate for such differences in stamp size and afford a pin-feed in which the pins in 10 variably register with the perforations of the stamp-strip.

Figs. 6 and 7 especially show the mechanism for feeding the stamps. The head 30 and plate 31 bound the throat 25 that guides 15 the stamp strip tangentially to the stamp wheel 26, and the stamp wheel is rotatable upon the shaft 32 mounted in the head 30. The stamp wheel, as best shown in Fig. 7, has projecting from its periphery equally-spaced rows of center-apex, tapering pins 33 that at their tips are (circularly measured) slightly farther apart than the normal distance between perforation rows, and at their butts are slightly less apart than such stamp-perforation distance. Axially the pins correspond in spacing with the lateral separation of the perforations in the Government stamp strip. Between suitable groups of 20 the pins are formed peripheral grooves 34, one of which preferably occurs about the 25 middle of the wheel. The wheel 26 has fastened thereto a spur gear 35 by which it is driven, and of course the two wheels are independently rotatable on their shaft.

30 The upper portion 30 of the stamp head is cut away to give the wheel free clearance, except adjacent to the mouth 27, where it is provided with fingers 36 that reach in to the 35 grooves 34 of the wheel in order to strip 40 the stamps positively from the wheel. The shell section 30' completing the head 30 has ribs 38 that extend between pins of adjacent courses on the wheel, and that are clear of the periphery of the wheel body to leave a 45 stamp-strip clearance of material depth. This shell section is suitably cut away, as at 50 39, opposite one of the grooves 34 of the wheel, and its edge 40, which forms a lip of the mouth 27, is sharp-edged to facilitate 55 tearing off the stamp strip upon ejection of a stamp. The parts are so arranged that the stamp wheel, in its normal operation, always stops, as shown in Fig. 6, with a row of pins directly opposite the tearing edge 40, and in practice it is found that however 60 carelessly one may tear off the ejected stamp or stamps, the last ejected stamp tears clearly along the perforated-line adjacent edge 40.

65 With respect to the coöperation of the wheel and ribbed casing, it will be seen from Figs. 8 and 9 that the stamp strip *a* may take various positions with respect to the tapered, center-apexed pins 33 in the clearance space provided between the ribs 38 of

the shell and the surface of the wheel. If the tip of the pin can engage the perforation at all, as shown in Fig. 10, then accordingly, as the stamp, which is having its rear edge so engaged, is long or short, said stamp will 70 be carried forward, so to speak, by the newly engaged pin, if the stamp be long, or backward, if the stamp be short. Thus variations in lengths of the individual stamps of the strip, at least within about half of the 75 diameter of a stamp-perforation, may automatically be accommodated without tearing or enlarging of the perforation, the longer stamps riding near the outer periphery of the clearance as shown in Fig. 9 and shorter 80 stamps near the inner periphery of the clearance, as shown in Fig. 8, and the requirements of space imposed by a freshly engaged stamp being compensated for more or less by shifting in or out of the stamp or 85 stamps in advance, already riding on the wheel. In practice the leeway thus afforded is found ample to accommodate the variations in stamp lengths as rolled stamp-strips are issued by the Government. Once a row 90 of pins engages a row of perforations, if only the bare points of the succeeding pins catch in the next row of perforations, the included stamp will ride in such position, either close to the periphery of the shell or close to the 95 wheel as best accommodates the stamp length, and through long passages of varying-length stamps the pins will work without ever getting out of register.

The provision of idler rollers 22, 22' for 100 the stamp-strip-rolls somewhat above the bottom of the tray in which said rolls rest both lessens the friction resistance to stamp feeding and tends to take up slack. As the down-course of the stamp strip is pulled 105 upon, the roll of stamps tends to and usually does ride up somewhat on the idler 22, which turns freely, and the braking action of the bottom of the tray against the roll is lessened or overcome. Furthermore when 110 the weight of the stamp roll causes it to drop back after a feed has taken place, the tendency of the roll is to tighten the forward and downward course of the un-rolled stamps and so "slack" is automatically prevented.

Stamp wheel selection and drive.

While the stamp-strip-handling construction hereinbefore described may be used in 120 many forms of stamp and ticket dispensing machines, wherein perforated strips are employed, these features are herein shown especially in a power-operated machine handling two strips selectively. In such multiple-strip machine the driving mechanism for the two stamp wheels may advantageously take form as shown herein.

An axially-fixed "stamp shaft" or drive shaft 45 for power operation is provided 130

and to it either of the two stamp wheels may be gear-connected alternatively, for operation of either wheel to eject a single stamp of its particular value pursuant to a 5 single complete rotation of said shaft 45. Thus the shaft 45 is connected through a suitable axially shiftable, connecting device 46 sliding on shaft 45 with axially shiftable extension shaft 47 that traverses the frame 10 20 and that has mounted thereon companion gears 48 and 48', either one of which, accordingly as the extension shaft is shifted fully to left or right, may coöperate with the appropriate gear 49 or 49' mounted on a 15 stud on the frame 20. The gear 49 is permanently entrained with the gear 35 that is mounted on one-cent stamp wheel 26, the train comprising pinions 51, 52 and 35. Similar provision is made with respect to 20 gear 35' of the other stamp wheel. Each train is so arranged that a single rotation of shaft 47 will result in feeding movement of the stamp-wheel that is entrained therewith through an arc included between two 25 successive rows of pins, this desideratum being accomplished in the particular construction by the train-proportioning and by the provision of intermittent gears 48 and 49. The stamp wheel may not be rotated inde- 30 pendently of shaft 45, for the hub and stripped portion of gear 48 coacts constantly, except when a wheel 49 or 49' is being driven, with a concaved locking projection 50 on gear 49 or 49'.

35. *Selection of the desired stamp strip.*

For manual control of the shiftable gearing described, so that the user may select the stamp strip from which delivery shall 40 be made, manual operating devices, such as buttons 55 and 55' are provided, these buttons having steps sliding through the front of the frame and preferably close to the displayed part of the respective stamp 45 strips. Each button, when pressed in under proper conditions may operate an appropriate selector lever 56 or 56' normally retracted by spring 56^a. The shoes, or elongated ends 57, 57' of these selector levers 50 coöperate with rollers 58, 58' on the ends of a pivoted shifter member 59 that preferably takes the form of a T-shaped or double-bell-crank lever, pivoted on a frame-piece 60, and the pendent arm 61 of which ex- 55 tends between the shoulders of the hubs 62 and 62' fast upon the axially shiftable shaft 47. Thus it will be seen with respect to Fig. 2 that if the right hand selector arm 56' be swung inwardly, its shoe 57', coöperating 60 with the roller 58', will tilt the shifter lever 59 throwing its arm 61 toward the left and thereby shifting the shaft 47 axially to the left to disengage gear 48 from gear 49 and engage gear 48' with gear 49', thus dis- 65 abling the left-hand or one-cent stamp wheel

and conditioning the right hand or two cent stamp wheel for operation when power is applied to the shaft 47. At their upper ends both levers 56, 56' have hubs 67, 67' making lost-motion clutch connection with 70 a clutch element 63 fast on a control-shaft 64, (functioning as hereafter described) so that when either lever is rocked the shaft is rocked but without disturbing the other lever. 75

Disabling and non-interference means.

For some purposes it is important that one or the other or both of the keys 55, 55' shall at times be disabled to affect the shifting mechanism, so that, when pressed inwardly, the button will merely slide idly, doing no effective work. 80

Thus the slide bar 68, rigidly connected with the button 55, (shouldered as at 69 and 85 sliding in guides in the frame) has pivotally supported thereon an elongated connector pawl 70, normally maintained in raised position by a spring 72, and provided with a shoulder 73, that, as long as the pawl is held 90 raised by its spring, may engage a stud 74, laterally projecting from the selector lever 56. With the parts in normal position shown in Fig. 1, the rearward movement of the button 55 causes immediate engagement 95 of shoulder 73 with stud 74 and consequent rocking of the appurtenant selector lever 56 and shaft 64. For working said pawls 70 in unison to move them out of the range of stud 74, a disabling shaft 80 is provided, extending transversely of the stamp section frame, carrying centrally a member 81, of a lost motion clutch that coöperates with kindred elements 82 and 82' otherwise free upon the shaft, each said element having an arm 83 100 that extends to and overlies the rear end of the appurtenant pawl 70 and each having also a forwardly extending arm 84 or 84'. When the shaft 80 is appropriately rocked, counter-clock-wise in Fig. 1, the lost motion 110 clutch will cause both arms 83 and 83' to be depressed and consequently both stamp buttons will have their connector pawls 70, 70' depressed so as to be incapable of swing- 115 ing their selector-levers 56, 56'. Either sec- 120 tion 82 or 82' of such clutch may, however, be rotated, by virtue of the lost motion connection with clutch member 81, to accom- 125 plish this disabling function with respect to its associated stamp button alone without affecting the shaft 80 or the other stamp but- 130 ton. The shaft 80 may be actuated from any suitable power source to effect its dis- abling action at any desired time, and illus- tratively, such shaft 80 is shown as con- trolled in its operation by a cam 85 on a shaft 86 of the machine with which the stamp section is associated, said cam 85 act- ing through roller shod lever 87, connected with the shaft 80 to rock the shaft to dis-

abling position during substantially the whole cycle of the cam except when the cam is in its normal or resident position. The cam wheel 85 thus typifies a suitable automatic mechanism for causing this disabling of both stamp buttons at predetermined desired periods. Further, for disabling the two-cent stamp button 55', alone, a rocker arm 90 having its ends overlying the pawl 70' is carried by a shaft 91 of the main machine, (Fig. 2) so that when said shaft is rocked, this two-cent stamp button alone is disabled.

Incidentally to the operation of shaft 80 by cam 85, the rocking of shaft 80 may be used to throw shifter arm 59 for the stamp wheel gearing to its left hand position, a lever 88 on shaft 80 carrying a link 89 that has slot and pin connection at 59^a with a projection from shifter lever 59 for this purpose.

For insuring that the stamp buttons shall be operable only alternatively, or without interference, I provide interlocking means between the buttons whereby the impressing of one button locks the other against inward movement. Specifically 93 is a T-shaped lever horizontally arranged and pivoted, as at 94, to a suitable frame part 95, said lever having projecting arms 96 and 96' beveled at their ends, and notched as at 97. Each such extremity lies in the path of movement of the shoulder 69 on the slide bar 68 of the contiguous stamp button so that the lever 93 is capable of being swung to the right by operation of the left hand button and vice versa, its movement to the left under the influence of the right hand button, say, interposing its notched portion 97 in the path of the shoulder 69 of the left hand button, so that the latter cannot be pushed inwardly until the right hand button has been retracted. In this way it is insured that both of the selector levers 56 and 56' may never be pressed backwardly at the same time and by this means also the effect of any effort on the part of the user to press both buttons in simultaneously is confined substantially to the sturdy slide bars, but tons and interposed locking lever, throwing no needless strain on the lighter mechanisms with which said parts are coöordinated.

Further, since a complete rotation of the stamp shaft 45 is to result from even a momentary in-pressing of either stamp-button 55 or 55', it is necessary to prevent a transposition of the respectively operative and idle connections of the two stamp wheels with respect to the shaft during the interval of shaft-rotation. To this end the axially shiftable element 46 establishing connection for rotation between stamp shaft 45 and its extension 47 bears a slotted flange 98 having a knife edge at one side of its slot arranged 65 to pass down one side or the other of a

fixed knife-edged retaining arm 99 (Figs. 2 and 5) as soon as the shaft 45 starts its rotation. Therefore, until the shaft rotation is completed no shifting of the extension shaft axially can take place.

In conjunction with the machine described I preferably provide automatic stop means for disabling appropriate machine parts in the event that stamps on the wheel of either section give out. The tester or explorer for the presence of stamps is the disk 100 working through the orifice 39 in the stamp wheel casing opposite one of the grooves 34 in the stamp wheel (the mechanism here described being of course duplicated with respect to the other wheel). This disk 100 is carried by a link 101 that is pivoted at its upper end for lateral movement should the disk 100, in the absence of stamps on the stamp wheel, drop into the groove 34, and the link is also capable of vertical movement, to operate certain disabling mechanism, there being provided means automatically to give the vertical movement to said link only when the first said lateral movement has taken place. Thus the link 101 is pivotally mounted on a crank arm 102 carried by a shaft 103, the pivoted link being normally drawn by a spring 104 so that its disk 100 rests on the stamp strip. The said shaft 103 carries one element, 105, of a lost motion clutch, the other elements of which are the hubs 106 and 106' of the two levers 102 and 102'. If either of said levers be raised, the appropriate clutch will cause the shaft 103 to be turned, and a crank arm 107 on the extremity of said shaft will coöperate with a crank 108 on a suitable shaft 109 to rock said shaft 109 for desired machine-disabling purposes. Also, either stud 110 or 110' of the respective arms 102 or 102' will rock the corresponding lever arm 84 or 84' so as to disable, in the fashion heretofore described, the connection between the appurtenant stamp button and its selective lever, thus insuring that that stamp button cannot effectively be worked further, although the other stamp button is not disabled.

For elevating the link 101 whenever its exploring wheel 100 has moved laterally because of the absence of stamps from the stamp wheel, a pivoted lever 120 is provided, acted on by a spring 121 to hold a roller 122, carried on one arm of the lever, in engagement with a cam 123 on extension shaft 47 of the stamp-shaft, there being on the other extremity of the lever an upturned finger 124 having a path of vertical movement that normally excludes the position of a pin 125 carried by the link 101, but that includes the position of said pin when the link has been laterally shifted. Thus, when the stamps are exhausted from the wheel, link 101 swings over the right, Fig. 6, and

then the cam-impelled vibration of lever 120 that occurs during each rotation of the stamp wheel, results in the elevation of the link 101. Said link when raised, is latched 5 in elevated position through the engagement of notch 127 in the link with a latch abutment 128 of a suitable pawl structure 129.

General combinations and operation.

- 10 It will be understood that a stamp delivery section providing the features of construction and coördination of parts hereinbefore described may be used in various stamp or ticket delivering mechanisms, in 15 association with suitable coin controlled parts, preferably, so as to make the complete structure a coin operated vending machine. The specific vending machine construction with which this stamp-section has been employed is in itself somewhat intricate and involves many features not germane to the present invention, so that, in lieu of illustration of complicated mechanism and merely for purposes of full expression of one useful 20 coördination of all of the parts heretofore described, in some instances requiring the presence of instrumentalities that structurally form part of the coin-controlled apparatus, Fig. 2^a illustrates diagrammatically 25 only sufficient complementary parts and appliances to indicate one of the many possible utilities of the stamp-section mechanism. Such diagrammatic showing will be described incidentally to the following résumé 30 of the operation of the parts heretofore described.
- 35 Assuming that the stamp section is employed in conjunction with a suitable structure intended to receive only 25 cent coins, 40 say, in consideration whereof 24 cents' worth of stamps are to be delivered by the machine, the coin 150, when inserted in chute 151 that is normally covered by the chutedoor 152, may close a switch 153 controlling 45 the circuit 154 for a motor 155, which is geared suitably to drive the cam shaft 86. A latch 156 for the switch 153, controlled by a releasing lever 157 associated with the cam 158 on the cam shaft 86 typifies means 50 for maintaining the circuit 154 closed until the cam shaft has completed a single revolution, whereupon cam 158, releasing latch 156, will cause breakage of the circuit and cessation of operation of cam shaft 86. The 55 cam shaft 86 may do any useful work in the vending machine structure, as typified by its illustrated function of opening a coin-passing gate 160 in the chute 151 by the operation of a cam 161 on a link 162 connected with the gate. Also it operates parts 60 of the stamp section. Thus, during the cyclic operation of this cam shaft its cam 85, as heretofore described, operates arm 87 to rock the shaft 80 thereby to bring 65 the shifter lever 59 to left-hand position,
- through the connections 88, 89 and 59^a, normally and also the rocking of said shaft 80, through clutches 81, 82, 82', rocks both levers 83 and 83' to depress connector-pawls 70 and 70' so that the buttons 55 and 55' 70 are disabled to operate their respective levers 56 and 56'. When cam 85 completes its cycle of movement, pawls 70 and 70' are restored to operative relation to levers 56 and 56' and the machine is then ready to 75 begin its stamp-delivering operations.

Typifying the fact that the cam shaft 86 may also control in part the potentiation of the stamp wheel driving parts for operation, so that an operation of the cam shaft 80 is a prerequisite to delivery of each batch of stamps, the cam shaft 86 is shown as provided with a cam 164 that, at the end of the complete cycle or revolution of shaft 86, closes a switch 165 that is included in series 85 with switch 166 in a circuit 167 for a motor 168 that through appropriate gearing drives the stamp shaft 45. This switch 165, cooperating with latch 169 will be released, as hereafter described, when a full batch of 90 stamps has been delivered, so that another operation of the cam shaft must precede the delivery of a further batch of stamps. Thus, until the cam shaft has completed its cycle of revolution and so has closed the 95 switch 165, (which is thereupon latched closed by the latching device 169,) the switch 166, itself operated by a lever 170 on control shaft 64, cannot start the motor for the stamp shaft 45.

100

Referring to the stamp section heretofore described it will be observed that, after the cam shaft 86 has completed its revolution, if either stamp button 55 or 55' be pressed in, the elongated pawl 70 or 70' carried by the button-slide engages the appropriate lever 56 or 56' and rocks the latter rearwardly, so rocking the control shaft 64. Lever 170 on said shaft thereupon closes the switch 166, completing the circuit for motor 68 and causing the commencement of operation of the stamp shaft 45. Switch 171 in a shunt connection 172 may be controlled by a cam 173 on the stamp shaft 45 so that when once the circuit for the motor 168 is closed, it remains closed until the stamp shaft has made a complete revolution. Thus, after the preliminary operation of the cam shaft 86, each time either stamp button is pressed in, a complete rotation of the stamp shaft 45 ensues, 105 and if the stamp button be held continuously pressed in, maintaining the circuit 167 closed, then the stamp shaft 45 will continue to rotate uninterruptedly until something (herein indicated as the release of the latch 110 169 and consequent opening of switch 165) intervenes to discontinue the operation.

115 It will now be apparent that whenever a proper coin has been inserted, initiating a single rotation of cam shaft 86, and said 130

shaft has come to rest, potentiating the parts to respond to the operation of the stamp buttons, the momentary in-pressing of either stamp button will cause a complete 5 single rotation of the stamp shaft 45. Therefore, until the release of the latching device 169 occurs, (this taking place when the 24¢ credit has become exhausted as herein-after described) the two stamp buttons may 10 be operated alternatively at will, so that a user may take all two cent stamps, all one's, or—several two's, some one's, more two's and more one's in any order he pleases. In 15 short until the credit is exhausted the number and order of each variety of stamps taken rests wholly with the will of the user. Both stamp buttons may not be simultaneously pressed in, because the swinging plate 93 can allow only one slide at a time 20 to be pressed in.

The rotary motion of the stamp shaft 45 is communicated to either the two cent stamp wheel or the one cent stamp wheel, according to the selective operation of the 25 buttons 55' or 55. If button 55 be pressed in, it is the lever 56 which is moved rearwardly, while lever 56' remains idle, owing to the lost motion connection afforded between clutch parts 62' and 63. Consequently shoe 57 of lever 56 operates the shifter lever 59 to throw the gearing parts into the position illustrated in Fig. 2, wherein gear 48 fast on the axially shiftable extension 47 of stamp shaft 45 is engaged with 30 gear 49 to communicate motion through the train 51, 52, 35 to the left hand or one cent stamp wheel 26, the gearing being such that for each complete rotation of the stamp shaft, said wheel 26 delivers a single stamp 35 through the orifice 27. Once shaft 45 starts its rotation, the slotted disk 98 and arm 99 prevent intentional or accidental shifting of the extension shaft 47 until the stamp-shaft rotation is complete and arm 99 again registers with the slot in disk 98.

The rotary motion of stamp shaft 45 is translated into a stepping motion of shaft 175, which I term the "penny" shaft. As the extension shaft 47 shifts to right or left, 50 to cause two cent stamps or one cent stamps, respectively, to be delivered, the shiftable gear connection 46 coördinately changes position, to cause the single-arc intermittent gear 176 or double-arc gear 176' to mesh with 55 the multiple-arc gear 177 on shaft 175 that is to be stepped forward. One step of said shaft 175 occurs for each rotation of stamp shaft 45 when one cent stamps are being delivered and two steps for each rotation of 60 said stamp shaft 45 when two cent stamps are being delivered.

The shaft 175, thus operating step by step, in accordance with the value of the stamps delivered, may perform useful work in connection with computing mechanism or other-

wise. For instance, as illustrated the value counter 178 in Fig. 2^a, may operate to indicate at all times the monetary value of the stamps dispensed. Also such shaft may perform useful functions in limiting the value 70 of stamps dispensed to such amount as is consistent with the coin inserted and also in disabling the two cent stamp delivering mechanism when stamps taken out amount to only one cent less than the maximum 75 amount due. Merely to typify such functions and to indicate that the delivery of stamps may be restricted accurately to the monetary value predetermined (say 24¢) by the character of the coin employed, said 80 stepping shaft 175 is shown as driving step by step a shaft 180, through gearing 181, by which said shaft 180 is caused to make one full revolution in response to twenty-four steps of shaft 175 in delivering twenty-four 85 cents' worth of stamps. The last said shaft 180 is shown as returnable by spring 182 to normal position. It may be stepped forward a predetermined distance for each step movement of shaft 175, and held by a 90 pawl 183 coöperating with a ratchet 184, on said shaft 180. To insure resetting of said shaft 180 to zero position before the delivery of stamps in consideration of the inserted coin begins, the pawl 183 is shown 95 as releasable by connection 185 operated by the cam 158 in the course of the preliminary cycle of the cam shaft 86. When the shaft 180 reaches a position twenty three steps in advance of normal, a cam 186 thereon, operating a lever 187 pulls down a link 188 connected to a crank 189 on the shaft 91, and said shaft 91 through its lever arm 90 depresses the elongated pawl 70' for the two cent stamp slide so that the operating shoulder 73' of said slide, which makes working engagement with the stud 74' on the lever 56', is thrown out of engagement or possibility of engagement with said stud, and consequently two cent controlling lever 56', 110 if theretofore pressed in is spring retracted, or if theretofore idle is positively disabled, so that under these conditions, when there is only one cent credit left to be exhausted, the two cent stamp button is disabled, but 115 the one cent stamp button is left operative. As the last step movement (the twenty-fourth under the present hypothesis) of the shaft 180 is being made its cam 186 by further moving the lever 187 works through 120 suitable lost motion connection 190 to release the latch 169 for the controlling switch 165 so that, when the stamp shaft 45 has completed its final or twenty-fourth cycle and the shunt switch 171 opens, the 125 electrical connections necessary for operation of the machine are completely destroyed and the cycle operation of the machine is completed, so that machine-operation may be resumed only upon insertion of a new 130

coin and a recommencement of the described cycle.

Should a stamp strip for either stamp wheel become broken, the machine automatically disables the affected portion of the machine preferably in a fashion that will prevent users from inserting coins, as by the locking of the coin-chute door 152, and by disconnecting the affected stamp button 10 from its control of the empty stamp-wheel. When either stamp strip becomes broken or exhausted, so that only one stamp remains to be fed by the appropriate wheel, the groove 34 of said wheel is then left open, 15 and the exploring disk 100 on link 101 finds free passage into the said groove. Consequently when the next rotation of the stamp shaft 47, in delivering the last stamp, causes cam 123, acting through lever 120, to 20 raise said link by virtue of finger 124 striking the pin 125 of said link, the lever arm 102 (Fig. 1) is elevated and it is held in elevated position by the engagement of notch 127 in the link 101 with the retaining 25 element 128. The rocking of the shaft 103 occasioned by this movement of lever 102, raises lever 107, so rocking the lever 108 carried by shaft 109 and said shaft, through a latch member 191 (Fig. 2a) locks the coin 30 door closed. Also this upward movement of lever 102 operates arm 84 of the affected delivery element, so tripping the elongated pawl 70 or 70', as the case may be, and disabling, as heretofore described, the appurtenant stamp button against operating 35 its lever 56. This, it will be observed, leaves the other stamp button free for operation to cause delivery of stamps to satisfy, as nearly as may be, the credit existing in 40 the machine, but after this transaction the machine may not again be used until the stamps have been replenished, because once the link 101 is raised it is positively latched in raised position at 128, so locking the coin 45 door until an attendant comes to refill the machine and release link 101.

While a particular stamp-section mechanism has been herein described in considerable detail, in conjunction with specifically-suggested instrumentalities illustrative of a coin controlled apparatus for full embodiment of the present invention, it will be understood by those skilled in the art that many changes in detail of the mechanical 50 structure of the stamp section might be made without departure from the spirit of the invention and within the scope of the appended claims, and that mechanical and electrical equivalents and refinements of 55 parts diagrammatically suggested may be employed, within the scope of the claims.

Having described the invention, what is claimed is:—

1. In a handling mechanism for perforated stamp strips, a casing having an en-

trance opening and an exit opening more than a stamp length removed therefrom, said casing having its peripheral wall between the entrance and exit grooved, and a delivery wheel having rows of projecting pins 70 whereof the tips are separated, circularly, slightly more than normal stamp-length and the butts are separated slightly less, said pins of a row registering with grooves of the casing wall and said casing 75 wall being spaced apart from the wheel to leave a clearance space wherein the stamps may ride at different elevations on the pins, compensating for differences in stamp length.

2. In a handling mechanism for perforated stamp strips, a casing having an entrance opening and an exit opening provided with a tearing lip at its lower edge more than a stamp length removed therefrom, said casing having its peripheral wall between the entrance and exit grooved, and a delivery wheel having rows of projecting pins 80 whereof the tips are separated, circularly, slightly more than normal stamp-length and the butts are separated slightly less, said pins of a row registering with grooves of the casing wall and said casing 85 wall being spaced apart from the wheel to leave a clearance space wherein the stamps 90 may ride at different elevations on the pins, compensating for differences in stamp length, power operated means for rotating said wheel step by step to stop invariably with a row of pins closely confronting said 95 tearing lip of the outlet orifice and means for preventing rotation of the wheel save through said power operating means.

3. In a mechanism of the character described, the combination of a stamp delivering means, means to operate same, lever means controlling the connection of the operating and delivery means, a manually operable actuating part for said lever means, a connecting pawl for connecting said manually operable part and the lever means, and means to move said pawl out of position for such connection.

4. In a mechanism of the character described, the combination of a stamp delivering means, means to operate same, lever means controlling the connection of the operating and delivery means, a manually operable actuating part for said lever means, a connecting pawl for connecting said manually operable part and the lever means, and means operable upon rupture of the stamp strip to move said pawl out of position for such connection.

5. In a machine of the character described, 125 a plurality of stamp delivery wheels, common means to operate them, means including a pawl for manually establishing connection of any wheel with the operating means, and means, operable upon absence 130

of stamps from any wheel for moving to non-connecting position the pawl appurtenant to the manually operable means for such wheel.

5 6. In a machine of the character described, a pair of stamp wheels, a drive shaft therefor, shiftable gearing for connecting either wheel to said drive shaft, a pivoted gear shifter having oppositely extending arms, pivoted levers above said arms to depress one or the other when the appropriate lever is moved, and push buttons controlling said levers.

10 7. In a machine of the character described, a pair of stamp wheels, a drive shaft therefor, shiftable gearing for connecting either wheel to said drive shaft, a pivoted gear shifter having oppositely extending arms, pivoted levers above said arms to depress either as the appropriate lever is moved, reciprocating manually operable means controlling said levers through connecting pawls and means for throwing said pawls to disconnected position.

15 8. In a machine of the character described, a pair of stamp wheels, a drive shaft therefor, shiftable gearing for connecting either wheel to said drive shaft, a pivoted gear shifter having oppositely extending arms, pivoted levers above said arms to depress either as the appropriate lever is moved, reciprocating manually operable

means controlling said levers through connecting pawls and means for throwing said pawls to disconnected position, in unison or 35 individually.

9. In a machine of the character described, a control shaft 64, levers mounted thereon, each free to permit the shaft to move and each connected to move the shaft 40 as the lever is moved; gear shifting means controlled by said levers, slide buttons for manual operation and pawls for connecting said buttons and the levers.

10. In a machine of the character described, the combination of a pair of stamp wheels, an operating shaft therefor, axially shiftable means to connect either wheel with the shaft, a vertically pendent lever for said shifter having opposite, laterally extending 50 arms, pivoted levers above said arms each having a cam foot to coact with the arm, manually operable slides for rocking said levers, and a pivoted T-shaped interlocking plate between said slides to prevent inward 55 movement of either lever while the other stands in-pressed.

In testimony whereof I hereunto set my hand in the presence of two subscribing witnesses.
